UNITED STATES PATENT OFFICE.

CARL GEORGE HILGENBERG AND HENRY REEVES LOPER, OF BALTIMORE, MARYLAND, ASSIGNORS TO THE CARR-LOWREY GLASS COMPANY, OF SAME PLACE AND NEW YORK, N. Y.

DENTIFRICE-BOTTLE.

SPECIFICATION forming part of Letters Patent No. 660,435, dated October 23, 1900.

Application filed February 3, 1900. Serial No. 3,864. (No model.)

To all whom it may concern:

Be it known that we, CARL GEORGE HILGENBERG and HENRY REEVES LOPER, residing at Baltimore, in the State of Maryland, have 5 invented a new and Improved Dentifrice-Bottle, of which the following is a specification.

Bottles in which dentifrices in the form of powder or liquid are commonly sold have usually comprised a glass body and a metal 10 cap with a cork stopper attached. The metal is liable to become corroded and tarnished when the goods are kept in stock for a considerable time, whereby the bottles become so deteriorated in appearance as to be unsalable. Labels are also generally applied in the first 15 instance to the necks of such bottles for the purpose of covering and concealing the cork. Bottles have also been provided with stoppers or plugs held in place by a sort of bayonet-joint; but the construction was objectionable for various reasons. Plugs have likewise been 20 constructed with central openings or passages having removable valves. We have devised an improvement upon all these forms 25 whereby new results and advantages are attained.

In carrying out our invention we have devised a novel construction and combination of parts, as hereinafter described. 30 In the accompanying drawings, Figure 1 is a side view of our improved bottle. Fig. 2 is a central longitudinal section of the upper portion of the bottle. Fig. 3 includes perspective views of the bottle-neck, the stopper, 35 and its plug or valve detached from each other.

The large neck 1 of the glass body 2 of our bottle has a coarse interior screw-thread 3, formed adjacent to the top or upper edge. 40 The glass cap or stopper 4 has a corresponding exterior thread and a lateral radial flange 5, which rests on the top of the bottle-neck 1 when the stopper 4 is screwed into place. The threads 3 3' are made very coarse and short, 45 and the cylindrical body of the stopper is made as short as possible, so that the stopper may be inserted or removed by a slight turn or rotating movement. By making the stopper short an economy is also attained in the

manufacture of the bottle. The said cap or 50 stopper 4 is provided with a central vertical extension 6 and a discharge opening or passage 7 therein, as shown. This opening 7 is cylindrical and has no indentation or cavity in which the contents of the bottle can find 55 lodgment.

The plug or valve 8 has an enlarged head or lateral flange and a cylindrical body 9, adapted to fit neatly in the extremity of the discharge-opening 7 of the stopper 4, as shown 60 in Figs. 1 and 3. The said body 9 of the plug has a circumferential groove 10, (see Fig. 3,) and a notch 11 is provided in the adjacent lower portion of the same. This construction adapts the plug or valve 8 to engage or lock 65 with a small conical projection 12, formed on the interior of the bottle-neck 1, Fig. 3. In inserting the plug 8 it is manipulated, so that the conical projection 12 passes up through the notch 11 and into the groove 10, when 70 slight rotation of the plug 8 will obviously produce a locking engagement, so that it will be held securely in place.

It is apparent that to remove the plug 8 requires practically a reversal of the movement 75 by which it was inserted.

The groove 10 forms a complete circle, which arrangement enables it to be readily cleaned by running a string around the valve. The rotation of the latter in the stopper may 80 also produce practically the same result by reason of the projection 12 traversing the groove.

It will be observed that the body 9 of the valve or plug 8 is made as short as possible, 85 and the projection 12 is also located close to the top of the discharge-passage 7. This construction economizes material and reduces cost of manufacture, as before stated in the case of the stopper 4. The same advantage 90 results from dispensing with the usual lip or collar on the bottle-neck. The lateral projection of the flange 5 of the cap or stopper 4 practically takes its place.

The bottle is designed chiefly for holding 95 dentifrices in the form of powder, but when employed for holding liquids a cork washer 13 is required, the same being perforated and

applied to the body of the plug, as shown. One may also be applied between the stopper 4 and the bottle-neck.

By the above-described construction we provide a bottle which cannot become corroded or otherwise tarnished, is more ornamental and attractive in appearance, and therefore more salable than those usually employed for the same purpose and which 10 may be produced at less cost.

A special advantage is obtained by the provision of the stopper 4 with a central cylindrical passage having a corresponding valve, both stopper and valve being securely held 15 in place, yet adapted for easy detachment by rotary manipulation.

Having thus described our invention, what we claim, and desire to secure by Letters Patent, is—

20 1. As an improved article of manufacture, the dentifrice holder or bottle comprising the glass body having a neck with a cylindrical opening, the glass cap or stopper attached thereto by a screw-thread, and having a lat-

eral flange, and provided with a central cylindrical discharge-opening having a conical projection, and the plug or valve having an enlarged head, and a cylindrical body adapted to fit in the discharge-passage, and provided with a circumferential groove and a vertical 25 notch communicating therewith, the same being adapted to receive and engage with said projection, as shown and described.

2. In a dentifrice-holder, the combination, 30 with the stopper 4, having the vertical cylindrical passage 7, with conical projection 12, of the valve 8, having a cylindrical body adapted to fit in said passage, and a circumferential groove 10 extending completely 35 around it, and a notch 11 leading out and downward from said groove, as shown and described.

CARL GEORGE HILGENBERG.
HENRY REEVES LOPER.
